UNITED STATES PATENT OFFICE.

EDGAR I. GARSON, OF NEW YORK, N. Y., ASSIGNOR TO AMERICAN VENDING MACHINE COMPANY, A CORPORATION OF NEW YORK.

COIN-CONTROLLED MECHANISM FOR VENDING-MACHINES, &c.

965,290.

Specification of Letters Patent. Patented July 26, 1910.

Application filed April 10, 1908. Serial No. 426,278.

To all whom it may concern:

Be it known that I, EDGAR I. GARSON, a citizen of the United States, residing at New York, in the county of New York and State of New York, have invented certain new and useful Improvements in Coin-Controlled Mechanism for Vending-Machines, &c., of which the following is a specification.

This invention relates to coin controlled mechanism for vending machines, telephones, etc., and particularly to devices for preventing the fraudulent use of tokens, spurious coin, and even a genuine coin when considerably worn will be returned to the person attempting to use it without operating the coin controlled mechanism.

For the sake of brevity, I shall herein-after call the device a fraud preventer.

I will describe preferred embodiments of my invention and then point out the novel features in claims.

In the accompanying drawings: Figure 1 is a side elevation of a fraud preventer embodying my invention. Fig. 2 is a vertical longitudinal section. Fig. 3 is a plan view showing the interior of the device some parts being removed. Fig. 4 is a vertical transverse view of what I shall call the carrier. Fig. 5 is a view similar to Fig. 2, but showing a different form of what I shall call a depressor. Fig. 6 is a horizontal section of the casing showing a modified form of slot in the bottom thereof. Fig. 7 is a vertical transverse section, showing the position of a coin when first introduced into the device and also the position of the gripping pins. Fig. 8 is a similar view showing the same parts in different positions.

20 indicates the outer casing of the fraud preventer, preferably rectangular in form and at least one or more of its sides being removable. Its bottom is provided with a longitudinal slot 21, which may be of uniform width throughout its length as in Fig. 4, or its width may be reduced at the receiving end of the device, as indicated in Fig. 6 by 21^a. The casing is secured in position over two chutes 22 and 23, the former being designed to guide the coin to the mechanism intended to be operated thereby, and the latter to guide tokens, spurious coin, etc., to a receptacle or tray which will be accessible to the person using the device.

The carrier is indicated by 24 and is open

at top and bottom as clearly shown in Figs. 55 4, 7 and 8. It is designed to rest upon the bottom of the casing and be reciprocated to and fro within the casing. Its two sides 25 are spaced apart a distance somewhat in excess of the thickness of the coin intended 60 to be used in the machine. A handle 26 is attached to it and extends through an opening in the end of the casing a sufficient distance to push the carrier from one end of the casing to the other. 65

One side of the casing is provided with an elongated slot 27 over which a plate 28 lies on the outside of the casing. A set screw 29 passes through one end of the plate and the slot into the carrier, as clearly shown 70 in Figs. 1 and 3. The plate is supported at its other end by a set screw 30 which passes through an elongated slot 31 into the side of the casing. The slots 27 and 31 must be of sufficient length to permit the 75 carrier to move from one end of the casing to the other. The carrier is normally held at the receiving end of the casing by a coiled spring 32 secured at one end to the plate 28 and at its other end to the casing. 80 The carrier is partially closed at one end by the handle 26 which fits between its sides and is secured thereto by rivets or screws 33, see Fig. 2, or in any other suitable manner. The other end of the carrier is partially closed by a block 34 which may fit 85 against the ends of the sides as shown in Fig. 2, or between them as in Fig. 5, and be secured to the sides by any suitable means. In either case it is intended that the distance 90 between the inner end of the handle 26 and the opposing face of the block 34 shall be slightly in excess of the diameter of the coin intended to be used.

The sides 25 of the carrier are each provided with a hole 35 through which project pins 36 carried by plate springs 37 secured respectively at their upper ends to the two sides 25 of the carrier and normally lying flat against the outer surface of the sides as shown in Fig. 4. Each side 25 is reduced in thickness at its lower end to form a space 38 between the lower ends of the springs and the sides. On the bottom of the casing are secured two pairs of oppositely disposed cams 39 and 40, the cams of each pair being on opposite sides of the slot 21, and when the carrier is at the re-

ceiving end of the casing the cams 39 will have entered the spaces 38 and forced the springs 37 outwardly to a sufficient extent that the pins 36 will not project into the space between the sides 25 and thus leave the carrier unobstructed to receive a coin, as shown in Fig. 7.

The top of the casing is provided with an upward extension 41 provided with a curved slot 42, the outer end of which is intended to receive the coin and the inner end of which will deliver it to the carrier.

Assuming now the machine is intended to be operated by a nickel (five cents), the width of the slots 42 and 21 and the space between the two sides 25 of the carrier will be slightly greater than the greatest thickness of a new coin, and the part 21^a of the slot 21 will be of less width than the thickness of an acceptable coin to prevent it from falling through into the chute 23 when first introduced into the carrier. When the slot 21 is of uniform width throughout its length, as in Fig. 3, one side of the slot is provided with an inward projection 43 which will prevent an acceptable coin from passing through from the carrier to the chute 23. I also employ what I term a depressor to operate upon the coin and depress it. If an acceptable coin is operated upon, it will be depressed as far as the pins 36 will permit it to move and if an unacceptable coin, token or a mere disk is operated upon, it will be depressed below the pins 36 and entirely released therefrom. In Fig. 2 the depressor is in the form of a bow spring 44 secured at one end to the top of the casing with its curved portion adjacent to the front end of the carrier and its other end extending up through an opening in the top of the casing and bent over to be supported by the top. This spring is of a width to pass freely between the sides 25 of the carrier and the lower part of its curved portion is normally below the plane of the pins 36. A set screw 50 may be employed to vary the tension of the spring 44. As shown in Figs. 2 and 5 these pins are semi-circular in cross section with the flat side downward. In Fig. 5 the depressor is in the form of a pivoted bar 45 having a curved portion 46 on its under surface at its free end and a spring 47, secured at one end to the casing and bearing at its free end on the upper surface of the free end of the bar 45, serves to force the free end of the bar downwardly and the block 34 serves to limit its downward movement. In this case also the lowest part of the curved portion is normally below the plane of the pins 36.

Assuming that the carrier is in the position shown in Figs. 2 or 5, the springs 37 and pins 36 will be in the positions shown in Fig. 7, being so held by the cams 39. If now, a coin be introduced into the slot 42 it

will drop into the carrier and assume the position shown in Fig. 7, where 51 indicates the coin. It may be observed that in practice the spaces between the sides of the carrier and the coin will be much less than shown in the drawing. Several features are exaggerated in the drawings for the sake of clearness. The coin is shown in section in Fig. 8 and is supposed to be an acceptable coin. As is well known nickels and other coins of the United States have a peripheral bead on each face such beads being indicated by 52 in Fig. 8. If now the carrier be pushed forward the cams 39 will release the springs 37 and they will then move the pins 36 inwardly into engagement with the coin. The coin will also be brought into engagement with the depressor and as soon as it is over the wide portion of the slot 21 it will be free to move downwardly and will then pass under the depressor which will force it down until the beads 52 come into contact with the pins as shown in Fig. 8 and when in such position the depressor will be lifted above its normal position and be exerting its pressure on the coin. The pressure of the depressor on the coin is in excess of the pressure exerted by the pins 36 thereon but is not enough to force the pins laterally to release the coin when the latter is acceptable. Consequently the coin will be carried forward until it is over the chute 22 when the cams 40 will act upon the springs 37 and move them and the pins 36 outwardly and release the coin which will then drop into the chute 22 and be guided thereby to the mechanism to be operated.

There are many kinds of fraudulent devices which have been used in attempts to operate coin-controlled mechanism and if they can only be made to reach the mechanism a large proportion will operate the mechanism as well as a genuine coin, irrespective of their weight diameter or thickness. Many of these fraudulent devices which have been successfully used are so thin that if an attempt was made to use them in my fraud preventer they would pass through the carrier and slot 21^a, or by the projection 43 directly into the chute 23. If a disk of the same diameter and thickness as a nickel, or of the same thickness but slightly different diameter were used and it had no peripheral bead it would remain in the carrier and be gripped by the pins 36, but the latter would not be able to hold it against the pressure of the depressor and it would be discharged into the chute 23. Again, in the case of disks having peripheral beads but which are not as thick as a nickel the same result will happen because the pressures of the springs 37 and the depressor will be so adjusted with respect to each other that the latter will overcome the former when operating upon anything except a coin of the proper

thickness and with well defined beads. A genuine coin of the proper denomination if considerably worn will be discharged into the chute 23, but this will not cause any loss 5 to the user since it will be returned to a receptacle from which he can remove it. In actual experience it is found that more than ninety-five per cent. of the fraudulent devices employed vary so much from the coin 10 for which they are substituted, either in thickness or lack of peripheral bead, that they could not be carried past the chute 23 by my fraud preventer.

Sometimes it may happen that a token or 15 fraudulent coin will be used that will become jammed in the narrow portion 21^a of the slot 21 or between the pin 43 and the opposing wall of the slot and this would stop the operation of the machine. In order to 20 prevent this I provide the carrier with a depending pin 55, in the present case shown attached to the handle 26, and this pin projects through the slot 21. If a token or other device becomes jammed in the narrow 25 portion of the slot the pin, when the carrier is moved forward, will engage such token or device carry it forward to the wide portion of the slot when it will pass through into the chute 23.

30 In the operation of the device it is intended that the carrier shall be moved at comparatively slow speed in order to give the different parts time to act properly. Sometimes, however, efforts will be made to 35 move the carrier rapidly by giving the handle a sharp blow on the end instead of pushing it. Such rapid movement of the carrier would often be sufficient to carry many forms of fraudulent devices beyond the 40 chute 23 and into the chute 22. I therefore provide means to positively stop the carrier over the chute 23 if moved with undue rapidity. A preferred means for this purpose is illustrated in Fig. 1, where it will be seen, 45 that the plate 28 is provided with a recess in its lower edge which terminates in a shoulder 57 near the rear end of the plate. Upon the side of the casing a dog is pivoted in such manner that its tail portion 58 will 50 overbalance its head portion 59. The head of the dog normally engages the lower edge of the plate 28 as shown in Fig. 1, and when the carrier is pushed forward at comparatively slow speed the tail of the dog, which 55 normally lies in position to engage the shoulder 57, will, as soon as the head of the dog is opposite the recess 56, drop sufficiently to let the shoulder 57 pass. If, however, the handle 26 is struck a violent blow the shoulder 60 57 will move forward so rapidly that the tail 58 will not have time to move out of its way and will therefore engage it and stop the carrier over the chute 23. The carrier must then be permitted to return toward its 65 normal position when the dog will be disengaged from the shoulder and the carrier may be moved forward in a proper manner.

In the following claims where I use the term "spurious coin" I intend to include therein any form of undesirable device that 70 may be used instead of a proper coin.

Having described my invention, I claim:

1. In coin controlled mechanism, a fraud preventer comprising a carrier to receive the coin, gripping devices on the carrier for engaging both faces of the coin, and means for forcing a spurious coin from between the gripping devices. 75

2. In coin-controlled mechanism, a fraud preventer comprising a carrier to receive the coin, gripping instrumentalities to engage the face of a coin, and means for forcing a spurious coin out of engagement with said face gripping instrumentalities. 80

3. In coin-controlled mechanism, a fraud preventer comprising a carrier to receive the coin, a coin gripping device on said carrier adapted to engage the face of a coin, and means for forcing a spurious coin out of engagement with said face gripping device. 85

4. In coin-controlled mechanism, a fraud preventer comprising a carrier to receive the coin, a spring gripping device on said carrier to engage the face of a coin, and means for forcing a spurious coin out of engagement with said face gripping device. 90

5. In coin-controlled mechanism, a fraud preventer comprising a carrier to receive the coin, coin gripping devices to engage the opposite faces of the coin, and means for forcing a spurious coin out of engagement with said face gripping devices. 100

6. In coin-controlled mechanism, a fraud preventer comprising a coin gripping device to engage the face of a coin, and means for forcing a spurious coin out of engagement with said face-gripping device. 105

7. In coin-controlled mechanism, a fraud preventer comprising a carrier to receive the coin, a pair of spring actuated gripping pins on the carrier positioned to engage opposite faces of the coin, and a spring actuated depressor located in the path of movement of the coin for engaging the edge thereof. 110

8. In coin-controlled mechanism, a fraud preventer comprising a carrier to receive the coin, a casing within which the carrier may be reciprocated, a pair of spring actuated gripping pins on the carrier positioned to engage opposite faces of the coin, a spring actuated depressor located in the path of movement of the coin for engaging the edge thereof, and means within the casing for disengaging the pins from the coin. 115

9. In coin-controlled mechanism, a fraud preventer comprising a fixed casing, a carrier within the casing for receiving the coin, said carrier having holes in its sides, plate springs secured to the sides of the carrier and carrying pins which normally project 120

130

- through the holes in the sides of the carrier to engage both faces of the coin, means for reciprocating the carrier within the casing and means for moving said pins outwardly 5 at both ends of the casing.
10. In coin-controlled mechanism the combination with two separated chutes, one for acceptable coins and the other for spurious coins, of a casing secured above the chutes 10 and having a slot in its bottom to discharge into said chutes, a carrier to receive the coin and supported to reciprocate within the casing, means for reciprocating the carrier, spring actuated pins positioned to engage 15 opposite faces of the coin, a spring actuated depressor located in the path of movement of the coin for engaging the periphery of the coin and forcing spurious coin from between the pins into the chute to receive them, 20 and means for spreading the pins apart to release a coin over the other chute.
11. In coin-controlled mechanism, and in combination, a movable coin carrier provided with coin supporting means, means 25 for forcing spurious coins only out of engagement with said supporting means at a predetermined point in the travel of the carrier, and means for releasing a good coin from said supporting means at another 30 predetermined point in the travel of the carrier.
12. In coin-controlled mechanism, a fraud preventer comprising a bodily movable coin gripping device to engage the face of a coin, 35 means to force a spurious coin only out of engagement with said gripping device at a predetermined point, and means for releasing the grip of said device on a good coin at a predetermined point.
- 40 13. In coin-controlled mechanism, the combination with a casing having a slot in its bottom narrower at one portion than the other, a carrier within the casing open at top and bottom for receiving coin and delivering it through the wide portion of the slot, means for reciprocating the carrier, and a pin on the carrier projecting into said slot for forcing a coin that may be jammed in the narrow portion of the slot into the 45 wider portion thereof.
- 50 14. In coin-controlled mechanism, a fraud preventer comprising a carrier for receiving a coin, means for reciprocating the carrier, and normally inactive means independent of 55 said carrier for restricting the movement of the carrier in one direction when operated under excessive speed.
- 60 15. In coin-controlled mechanism, a movable coin carrier adapted to receive and carry a coin to a predetermined point of delivery, and a gravity controlled latch adjacent the path of movement of said carrier and operable under excessive speed of the carrier to engage and restrict movement 65 thereof.
16. In coin-controlled mechanism, a fraud preventer comprising a casing, a carrier for receiving and temporarily supporting a coin, means for reciprocating the carrier, a plate provided with a shoulder movable with the 70 carrier, and a pivoted dog adapted to contact with said plate and having one end arranged to overbalance the other, said dog and plate being so formed as to permit the shoulder to pass when the carrier is moved 75 in one direction at normal speed but engages the shoulder and stops the carrier when the latter is moved in the same direction at excessive speed.
17. In coin-controlled mechanism, a fraud 80 preventing means comprising a reciprocating coin-receiving carrier, means on the carrier to engage a face of the coin and support the coin within the carrier, and means located within the path of movement of the 85 coin for changing the position of the coin within the carrier and releasing it from said coin supporting means.
18. In coin-controlled mechanism, fraud 90 preventing means comprising a reciprocating coin-receiving carrier, means on the carrier for supporting the coin within the carrier, and means located within the path of travel of the coin for changing the position of the coin within and relative to said coin 95 supporting means, said coin supporting means forming a barrier against the passage of a non-spurious coin from the carrier under the action of the position-changing means.
19. In coin-controlled mechanism, fraud 100 preventing means comprising a reciprocating coin-receiving carrier, means on the carrier for supporting the coin within the carrier, and means located within the path of travel of the coin for changing the position of the coin within and relative to said coin supporting means, said coin supporting means forming a barrier against the passage 105 of a non-spurious coin from the carrier 110 under the action of the position-changing means, and having a path of travel corresponding to the direction of reciprocation of the carrier.
20. In coin-controlled mechanism, fraud- 115 preventing means including a reciprocating carrier, means for selectively supporting a coin within the carrier during its reciprocation in one direction, and means located within the path of travel of and coöperating 120 with the carrier to restrict the length of reciprocation of the carrier during its coin supporting direction of movement when the carrier is moved at excessive speed.
21. In coin-controlled mechanism, fraud 125 preventing means including a reciprocating carrier, means for selectively supporting a coin within the carrier during its reciprocation in one direction, said carrier having a stop movable therewith, and means located 130

within the path of travel of the carrier and coöperating with said stop to restrict the length of reciprocation of the carrier during its coin supporting direction of movement

5 when the carrier is moved at excessive speed.

22. In coin-controlled mechanism, a fraud preventer comprising a carrier having means to positively engage and support a coin by its outstanding rim, and means to engage

and move a coin out of the carrier if it be 10 without such outstanding rim.

In testimony whereof I affix my signature, in presence of two witnesses.

EDGAR I. GARSON.
